UNITED STATES PATENT OFFICE

2,579,550

SHIRT

Arthur M. Cooper and Joseph Bening, Chicago,
Ill., assignors to Town Fashions Inc., a corpora-
tion of Illinois.

Application October 8, 1948, Serial No. 53,518

2 Claims. (Cl. 2—115)

1

This invention relates to a shirt, and particularly to a shirt worn in bowling or other activities where considerable arm movement is required.

In bowling and similar activities the violent and extensive movement of the arm causes considerable strain to be placed on the back of ordinary shirts. A pleat or other expandable structure has been provided in the shirt back to allow for expansion, but these pleats were ordinarily located near the center of the shirts and thus interfered with lettering or the like normally placed on the backs of athletic shirts such as bowling shirts to indicate team names, the names of sponsors, advertising material and the like. In the present invention the shirt is provided with an improved pleat construction located at the back thereof but adjacent the sleeves and arm holes. This provides a shirt in which substantially no strain is placed on the back during bowling or similar activities and leaves the major portion of the back unbroken so that lettering and the like can be placed thereon.

One of the features of this invention is to provide an improved pleat in the back portion of a shirt with this pleat being adjacent an arm hole for permitting substantially free movement of the arm of the wearer and the pleat being formed of overlapping folded material and opening outwardly and toward the adjacent arm hole; another feature of the invention is the provision of such a pleat wherein the pleat extends below the bottom of the arm hole; still another feature of the invention is the provision of such a construction wherein the pleat has its top edge extending substantially straight across the fold and the bottom edge sloped upwardly and outwardly, and the preferred construction being one in which the top edge is attached to the back portion of the shirt while the bottom edge is unattached to this back portion except at the outer end of the bottom edge and the rear edge is unattached to the back portion except at the top of this rear edge; and a further feature of the invention is to provide such a pleat in the back portion of a shirt with this back portion being formed of a yoke and a depending portion of material joined by a seam at a line below the top of the arm holes, wherein the pleat comprises one piece of material integral with the depending portion and turned inwardly normally to lie against the inner surface of the depending portion, and a second piece of material attached to the first piece at the top, bottom and inner edges thereof to form corresponding edges of the

pleat and extending beyond the pleat to the arm hole so that a portion of the edge of the arm hole is formed in this second piece of material; the bottom of said second piece of material outside said pleat being attached to the adjacent section of the depending portion, with the said top edge of the pleat being straight and attached at said yoke seam, the bottom edge being sloped upwardly and outwardly and unattached to the back portion except at the outer end of the bottom edge, and said inner edge of the pleat being substantially straight and unattached to the back portion except at the top inner edge. Other features and advantages of the invention will be apparent from the following description taken in conjunction with the accompanying drawings. Of the drawings:

Fig. 1 is a front elevation of a shirt embodying this invention.

20. Fig. 2 is a rear elevation thereof.

Fig. 3 is a fragmentary elevation showing a pleat from the inner side of the back of the shirt and the material adjacent said pleat.

Fig. 4 is a fragmentary elevation similar to Fig. 25 but showing the assembled portions of the shirt forming the pleat prior to the stitching thereof.

Fig. 5 is a fragmentary elevation showing the material blanks prior to their assembly for forming a pleat, and the adjacent portions of the blanks.

30. Fig. 6 is a section taken along line 6—6 of Fig. 3.

The pleats of the shirt shown and described herein permit free movement of the arm or arms of the wearer so that substantially no strain is placed on the back of the shirt. These pleats have a pleasing appearance and are so constructed that when the arms are at rest the pleats immediately assume their normal shape so that the back of the shirt is smooth and even and there is no "gaping" of the pleats.

In the embodiment of the invention shown in the accompanying drawings the shirt includes a front portion 10, a back portion 11 formed of a top yoke 11a adapted to be arranged across the shoulders of the wearer and a depending portion 11b stitched to the bottom of the yoke 11a, and a collar 13.

Located adjacent each sleeve 12 is a pleat formed of overlapping folded material and opening outwardly and toward the arm hole to which the sleeve is attached. Each pleat is preferably formed of one piece of material 11c formed integrally with the depending portion 11b, with this piece of material turned inwardly normally to lie

along the inner surface of the depending portion 11b, and a second piece of material 14 attached to the first piece 11c at the top, bottom and inner edges thereof to form corresponding edges of the pleat. This second piece of material 14 extends beyond the pleat to the arm hole 15, and a portion of the edge of the arm hole is formed therein. The bottom of the second piece of material 14 is attached to the adjacent section of the depending portion 11b as by stitches 14a. The top edge 16 of the pleat is approximately straight and is attached at the seam between the yoke 11a and the depending portion 11b of the shirt. The bottom edge 17 of the pleat is preferably sloped upwardly and outwardly, as shown in Fig. 3, and is unattached to the depending portion 11b of the shirt except at the right hand end of this bottom edge, as shown in Fig. 3. The inner edge 18 of the pleat is substantially straight and is unattached to the depending portion 11b of the shirt except at the top of this inner edge where it joins the top edge 16. As can be seen in Fig. 3, the second piece of material 14 extends down and is unattached to the depending portion 11b of the shirt.

The steps required in making one of the pleats are illustrated in Figs. 3, 4 and 5. As is shown in Fig. 5, the depending portion 11b of the shirt is shaped with an outwardly extending piece of material 11c. This piece of material is provided with a bottom edge 17 sloped upwardly and to the left when the piece 11c is fully extended, as shown in Fig. 5, and is adapted to be turned back upon the adjacent section of the depending portion 11b. The second piece of material 14 is placed over the piece of material 11c, as shown in Fig. 4, so that the adjacent outer edges of these pieces are substantially aligned. The pieces of material 11c and 14 are stitched together, as shown in Fig. 3, to form the top edge 16, bottom edge 17 and inner edge 18 of the pleat. The second piece of material 14 is then attached to the depending portion 11b, as indicated at 14a, to complete the assembly. The arm hole 15 has a portion thereof formed in the second piece of material 14, while the outer edge of this second piece of material is aligned with the outer edge of the depending portion 11b to form the side seam of the shirt, as illustrated in Figs. 1, 2 and 3.

It is believed obvious from the above description that the new pleats permit a considerable degree of movement without placing the back of the shirt under undue strain. Each pleat is relatively deep so that considerable movement may be accommodated and as the top and bottom edges of each pleat are straight, the pleat readily assumes its folded position when the arms of the wearer are at rest. The bottom edge 17 of the pleat gives additional freedom of movement because of its upward and outward slope. As each pleat is formed of a part of the back portion of the shirt and an additional piece of material attached thereto, the shirts are very simple and economical to manufacture.

The new pleat construction of this invention may be used on shirts, dresses, uniforms, and the like.

Having described our invention as related to the embodiment shown in the accompanying drawings, it is our intention that the invention be not limited by any of the details of descrip-

tion unless otherwise specified, but rather be construed broadly within its spirit and scope as set out in the accompanying claims.

We claim:

1. In a shirt or the like having an arm hole at either side thereof and including a side portion and a back portion, a pleat in said back portion adjacent at least one arm hole for permitting substantially free movement of the arm of the wearer, said pleat comprising: one piece of material integral with said back portion and turned inwardly normally to lie along the inner surface of the back portion; and a second piece of material attached to the first piece at the top, bottom and inner edges thereof and extending beyond and outside said pleat to the arm hole, with a portion of the edge of the arm hole being formed therein and the bottom of said second piece outside said pleat being attached to the adjacent section of said back portion and to the adjacent section of said side portion, said top edge being straight and attached to said back portion, said bottom edge of the pleat being sloped upwardly and outwardly and free of the back portion except at the outer end of the bottom edge, and said inner edge being substantially straight and free of the back portion except at the top of the inner edge.

2. In a shirt or the like having an arm hole at either side thereof and including a back portion formed of a yoke and a depending portion of material joined by a seam at a line below the top of the arm holes, a pleat in said back portion adjacent at least one arm hole for permitting free movement of the arm of the wearer and extending from said yoke seam to a point below the bottom of said arm hole, said pleat comprising: one piece of material integral with said depending portion and turned inwardly normally to be along the inner surface of the depending portion; and a second piece of material attached to the first piece at the top, bottom and inner edges thereof to form corresponding edges of the pleat and extending beyond said pleat to the arm hole, with a portion of the edge of the arm hole being formed therein and the bottom of said second piece outside said pleat being attached to the adjacent section of said depending portion, said top edge being straight and attached to said yoke seam, said bottom edge of the pleat being sloped upwardly and outwardly and free of the back portion except at the outer end of the bottom edge, and said inner edge being substantially straight and free of the back portion except at the top of the inner edge.

ARTHUR M. COOPER,
JOSEPH BENING.
